SHOE HANGER

Eugene H. Hale, Dayton, Ohio

Application April 26, 1955, Serial No. 35,692

Term of patent 14 years

(Cl. D33—3)

Fig. 1 is a perspective view of a shoe hanger showing my new design;

Fig. 2 is a view thereof in side elevation; and

Fig. 3 is a bottom plan view of the shoe hanger.

I claim:

The ornamental design for shoe hanger, as shown.
